UNITED STATES PATENT OFFICE.

EUGENE FITCH, OF NEW YORK, N. Y.

TIME-INDICATOR.

SPECIFICATION forming part of Letters Patent No. 715,776, dated December 16, 1902.

Application filed January 3, 1901. Serial No. 41,942. (No model.)

To all whom it may concern:

Be it known that I, EUGENE FITCH, a citizen of the United States, and a resident of New York, county and State of New York, have 5 invented Improvements in Time-Indicators, of which the following is a specification.

This invention relates to time-indicators or clocks, and has for its object to provide improved means for successively exposing time-indicating plates.

According to my invention the time-indicating plates are pivotally mounted upon rotating parts in axial alinement with each other and with the minute-spindle of the clock-movement, whereby a simple construction and direct actuation of these rotating parts are attained, and according to my invention the same number of minute-indicating plates and hour-indicating plates is employed on rotating parts in axial alinement with each other, permitting the employment of the ordinary hour-hand reducing-gears to connect the two rotating parts and exhibiting the plates in the same plane and attaining a sufficiently 25 frequent movement of the hour-indicating plates to afford the desired accuracy of exhibition without impracticable accuracy of construction.

I will now describe the constructions of 30 time-indicators illustrated in the accompanying drawings and will thereafter point out my invention in claims.

Figure 1 is a perspective view of a clock or time-indicator embodying my improvements. 35 Fig. 2 is a central vertical section of the case, showing the clock-movement at one side of the case and part of the works in section and part in elevation. Fig. 3 is a view similar to Fig. 2, showing the clock-movement located centrally in the case and between the hour and minute indicating devices. Fig. 4 is a transverse sectional view looking toward the side of the indicating device; and Fig. 5 represents one of the indicating-plates detached, 45 showing one way in which they may be suitably made.

Any suitable ordinary clock-movement may be used, as shown at *a* in Fig. 2, where the movement is located at one side of the hour and minute indicating devices, and at *a'* in Fig. 3, where the movement is located between the hour and minute indicating devices. In both of these constructions the clock-move-

ment is arranged with its minute-spindle horizontal, but parallel with the front of the clock. 55 Only so much of the clock-movement is shown as is necessary to afford a correct understanding of its combination with the other features of my invention.

The hour-indicating plates *b* are marked or 60 impressed with numbers to indicate the hours, and the minute-indicating plates *c* are marked or impressed with numbers to indicate the minutes. Each of these plates is provided with two ears or projections, the projections 65 *b'* on the plates *b* and the projections *c'* on the plates *c* entering perforations in a pair of disks and by means of which each plate has a pivotal or hinged engagement with and is carried by such disks. The pair of disks *d d* 70 carries the hour-indicating plates *b*, and the pair of disks *e e* carries the minute-indicating plates *c*. These disks are mounted on a common axis in alinement with the minute-spindle of the clock-movement. As shown in 75 Fig. 2, the minute-spindle *f* is prolonged to extend across the case and has its outer end supported in the bearing-piece *h*, secured to the end of the case opposite the clock-movement. The disks *d*, carrying the hour-indicating plates, are secured upon a shaft or 80 sleeve *j*, which is loosely mounted on the minute-spindle, so as to rotate freely thereon. The disks *e*, carrying the minute-indicating plates, are suitably secured upon a shaft or 85 sleeve *i*, which is secured upon the minute-spindle, so as to rotate therewith. The hour-spindle *j* has secured upon it a gear *k*, which through intermediate gears *k'* is connected to and actuated by the pinion *l*, secured upon 90 the minute-spindle *f*, these gears being the ordinary hour-hand reducing-gears of a clock-movement. A squared end *f'* is provided on the minute-spindle for setting the plates in the same manner as setting the hands of a 95 clock, and a ratchet and pawl *m*, shown at the other end of the minute-spindle, are provided to prevent moving the cards backward. The winding-shaft of the clock-movement is shown at *a*.²

In the construction shown in Fig. 3 the hour-shaft *j* has a bearing at one end on the minute-spindle *f* and at the other end in the bearing-piece *h'* on the clock-case and is connected to the minute-spindle by reducing-gear *k k' l*, as in the construction shown in 105

100.

Fig. 2. The shaft *i* of the minute-indicating plates is coupled at one end to the minute-spindle *f*, as by a pin *i*², and at the other end is supported in a bearing-piece *h*² and has a squared end *f*² for setting the indicator-plates.

A winding-spindle *n* is shown in Fig. 3, having a squared upper end *n*', and at its lower end a bevel-pinion *o*, this pinion *o* meshing into a bevel-wheel *p*, secured to the motor device of the clock-movement.

The time-indicating plates will be sufficiently numerous to indicate by their successive exposure intervals of time sufficiently short for all practical purposes, and the same number of plates is provided to indicate the minutes and hours. I have shown as a suitable number sixty plates in each series, the minute series being figured or lettered consecutively from "1" to "60" or from "1" to "59" and one blank, so that each minute of time will be indicated, and as the disks carrying the hour-plates will rotate one-twelfth of a revolution to each revolution of the minute-disks the hour-plates *c* will be divided into sections similarly figured or lettered successively from "1" to "12," as indicated by the numerals arranged around the plates *c* in Fig. 4. Each minute-indicating plate will be exposed one minute and each hour-indicating plate will be exposed twelve minutes. It will be observed that two of the ten-hour plates are yet to fall, the time as indicated by the other views being ten hours forty-one minutes, and upon the passing of the sixty minutes then the last ten-hour plate will fall and the first plate of the eleven-hour section will be exposed at the same time that the "1" or the blank plate of the minute series is exposed, according to the arrangement of the minute-plates, whether they are to indicate the minutes lapsing or the minutes lapsed. The means for controlling the descent of the plates *b* and *c* as the carrying-disks rotate consist of the stops *q* and *r*, set in the front of the case or in brackets extending therefrom, against which stops the upper edges of the plates bear, as clearly shown at Figs. 1, 3, and 4, and from the lower ends of which stops the plates escape and fall over as the disks carrying the plates slowly rotate. To insure that the plates of the two sets shall fall in unison, it is desirable to make these stops *q* and *r* adjustable. To this end they are shown as fine-threaded screws, so that they may be readily and delicately set.

To fully protect all of the works, it is proposed to inclose the semicircular space through which the plates *b* and *c* fall, they being arranged as near the front of the case *g* as possible by a glass cover, which may be of any suitable shape, preferably semicylindrical, as shown at *s*, with the ends formed integral therewith and provided with a flange *s'*, by which it may be held in front of the case *g*. The means for holding this glass cover may be a light wooden frame *s*², which may be per-

manently secured, as by screws, to the front of the case or be provided with hinges and a latch, as are ordinary clock-fronts.

The time-indicating plates *b* and *c* may be made of cardboard, light metal, celluloid, or other suitable material and may have the pivoting-ears *b'* and *c'* as projections from one of their edges, as shown in the main views of the drawings, or the edges may be bound and reinforced by a metallic binding-strip *t*, as shown at Fig. 5, made somewhat longer than the edges of the plates, the projecting ends of which constitute the pivotal connections of the plates in their carrying-disks.

The adaptation to a time-indicator of series of plates consecutively exposed provides an advantageous and suitable display apparatus, the display matter, whether simply pictures or advertisements, being printed upon or attached to the rear faces of the plates, thus exposing to view a new subject as each of the plates falls in chronometrical order.

It is obvious that various modifications may be made in the constructions above particularly described within the spirit and scope of my invention.

What I claim, and desire to secure by Letters Patent, is—

1. In a time-indicator, in combination, a clock-movement, two plate-carrying rotating parts mounted in axial alinement with each other and actuated by the clock-movement, a plurality of time-indicating plates carried by such rotating parts and pivotally mounted thereon, the time-indicating plates carried by one rotating part indicating minutes and the time-indicating plates carried by the other rotating part indicating hours and both rotating parts carrying the same number of plates, and stops arranged to successively coact with such plates to cause them to be successively exposed.

2. In a time-indicator, in combination, a clock-movement, two plate-carrying rotating parts mounted in axial alinement with each other and with the minute-spindle of the clock, a plurality of time-indicating plates carried by such rotating parts and pivotally mounted thereon, the time-indicating plates carried by one rotating part indicating minutes and such rotating part being secured upon the minute-spindle, and the time-indicating plates carried by the other rotating part indicating hours, reducing-gearing whereby such other rotating part is actuated from the minute-spindle, each of such rotating parts carrying the same number of plates, and stops arranged to successively coact with such plates to cause them to be successively exposed.

In testimony whereof I have hereunto subscribed my name this 27th day of December, 1900.

EUGENE FITCH.
